UNITED STATES PATENT OFFICE

ALBERT G. SMITH, OF AKRON, OHIO, ASSIGNOR, BY MESNE ASSIGNMENTS, TO THE MILLER RUBBER COMPANY, INC., OF WILMINGTON, DELAWARE, A CORPORATION OF DELAWARE

TUBE MANDREL CHUCKING DEVICE

Application filed December 27, 1928. Serial No. 328,701.

My said invention relates to improvements in tube mandrel chucking apparatus or in other words, machines or apparatus for holding and rotating poles or mandrels carrying uncured tubes, such as are used for inner tubes of pneumatic tires, for the purpose of having applied thereto a fabric wrapping.

Heretofore, so far as I am aware, it has been customary to place the mandrels, carrying the uncured tube stock, individually in a lathe having means for engaging the mandrel ends and rotating the mandrel while the wrapping tape was helically wound thereon. This required starting and stopping the lathe and chucking and unchucking for each mandrel, and the lifting of the mandrels to and from chucking position, an operation which was slow and involved a material amount of manual labor.

The present invention aims to provide apparatus in which the tube carrying mandrels will be automatically fed to wrapping position, automatically gripped and rotated for wrapping purposes, and automatically discharged after the wrapping is complete, all during the continuous travel of the mandrels.

The invention further aims to provide a relatively simple economical and efficient form of apparatus by which a plurality of tube carrying mandrels may be rapidly and simultaneously wound with a minimum amount of labor.

With these and other objects in view, the invention includes the novel features of construction and arrangement and combination of parts hereinafter described and defined by the appended claims.

What I at present consider the preferred embodiment of the invention is illustrated in the accompanying drawings in which:

Figure 1 is an end elevation of the machine or apparatus.

Fig. 2 is a front elevation partly broken away.

Fig. 3 is a sectional elevation on line 3—3 of Fig. 2.

Fig. 4 is a central vertical section through the parts shown in Fig. 3.

Fig. 5 is a section on line 5—5 of Fig. 2.

Fig. 6 is a sectional detail of one of the cradle rollers and adjacent parts.

Fig. 7 is a section on line 7—7 of Fig. 6.

Fig. 8 is a detail plan view partly in section showing one of the presser rolls and adjacent parts, and

Fig. 9 is a detail plan view of the cooperating presser roller and adjacent parts.

Fig. 10 is a detail view of one of the turbines with the pick up member shown detached to illustrate the manner of assembly.

Fig. 11 is a section on line 11—11 of Fig. 10.

Fig. 12 is a detail illustrating (conventionally) the electric control switch.

The apparatus comprises an inclined feed table upon which a plurality of tube carrying poles or mandrels are supported and down which they are adapted to roll by gravity into position to be picked up and automatically carried through the arc of a circle by holding means which rotates them about their own axes during such orbital movement, while the tapes are being wound on the tubes, the operator having attached one end of the tape to the tube or mandrel and holding and guiding the tape (under the requisite tension), during the winding.

The mandrel carrier is driven from a suitable source of power, and is arranged so that when the mandrels have reached a certain point subsequent to winding, they are automatically released and dropped onto means such as an inclined table down which they roll by gravity to a point for convenient removal.

Referring by reference characters to the drawings above referred to, the numeral 1 designates a suitable frame to which is secured a prime mover such as an electric motor 2, from which a speed reducer 3 of any well known type (shown conventionally in Fig. 2), is driven by sprockets 4 and 5 and chain 6. The speed reducer is connected by a flexible coupling 7 of any approved type with a shaft 8 journaled in suitable bearings 9, 10, and 11, in the main frame.

Said shaft 8 is provided with sprocket wheels 12, 12' keyed thereon at opposite ends of the machine, and also with a pinion 13 fast thereon adjacent sprocket 12 for driving the

mandrel actuating parts hereinafter described. Above the shaft 8 is located a turret carrying shaft 16 journaled in suitable bearings 14 and 15 in the main frame, to which shaft 16 are keyed the turrets or frames 17 and 17'. One of these turrets 17 has fast thereto a spur gear ring 18 which meshes with and is driven by pinion or gear 13 on the shaft 8. Obviously the other turret 17' could be similarly geared to shaft 8 if the length of the machine was such as to entail undue torsional strain by driving both turrets from gearing at one end only.

The turrets 17 and 17' and mechanism carried thereby being identical, a description in the singular will apply to both.

Each turret is provided with a plurality of radially arranged and equidistantly spaced guides or recesses 17a, Fig. 5, (three being shown as a convenient number), adapted to receive the ends of the poles or mandrels, the turrets being provided adjacent these recesses with mandrel pick up hooks 19 adapted to pick up the mandrels in the manner hereinafter described.

Near the bottoms of these recesses are located stud shafts 20 (Fig. 5) rigidly affixed to the turrets, on which are journaled rubber faced rollers 21, 21', which project beyond the wall or walls of the recess and serve as mandrel supporting and driving rollers and which I term for convenience, cradle rollers.

The driving of these rollers is effected by mounting them on sleeves 22 which carry sprockets 22a, all of the sprockets of each turret being driven by a sprocket chain 23 Fig. 1 which in turn is driven by a central sprocket 24 journaled on shafts 16, as shown in Figs. 3 and 4.

Sprocket 24 is preferably made integral with a sleeve which forms the rotatable mounting and which carries fast on its other end (preferably integral), a sprocket 25 which is driven by sprocket chain 26 from sprocket 12 on shaft 8.

It is necessary that means be provided for pressing the mandrels against the driving cradle rollers 21, 21', with sufficient force to ensure their rotation by frictional contact against the resistance offered by the tension on the tape, and also that the recesses shall be unobstructed at the mandrel receiving and discharge points.

To accomplish this, I provide the following mechanism:

Each turret also carries adjacent each recess and on opposite sides thereof studs 26 and 27 (Figs. 5 to 9) on which are fulcrumed respectively lever arms 28 and 29 which carry at their free ends rubber covered rollers 30 and 31, designed, when the arms are swung inward to engage the mandrels and press them against the driving or cradle roll-

ers, while when swung outward, they leave the recesses free and unobstructed.

Lever arm 28 has rigidly connected to its supporting shaft a lever arm 32, Figs. 3 and 5, the two arms constituting a bell crank lever, and said lever arm 32 is provided with a roller 33 cooperating with a stationary cam 34. An adjustable link 35 connects lever arm 32 with lever arm 29, fast on the shaft carrying lever arm 29, and a tension spring 40, attached at one end to lever arm 32 and at the other end to turret 17, acts to cause the lever arms 28 and 29 to be swung towards each other for causing the rollers carried thereby to press the mandrel ends against the driving or cradle rollers. The stationary cam 34 on which roller 33 bears has a concentric raised part 34a terminating in inwardly deflected cam faces *a* and *a'*, these respective parts being so arranged that when a pair of recesses 17a have reached a position where they are over the rails or receiving runway 43, the roller 33 rides up the cam face *a* and the gripping rolls are swung out clear of the recesses to allow the wrapped mandrels to roll out onto and down the receiving rails 43, Fig. 1, and onto table 43a from which they may be removed as desired.

As the turrets continue to rotate, the gripping or pressure rollers are held open and when the pick up devices or hooks 19 reach the supporting rails 41, they engage the ends of the foremost mandrel as shown in Fig. 1. Further rotation of the turrets in a clockwise direction, Fig. 1, brings the recesses towards an upright position whereupon the mandrels drop into the recesses and rest on the cradle rolls.

Further movement of the turret causes the rollers 33 to leave the high part 43a of the cam and move inward along face *a* which permits the springs 40 to swing the levers 28 and 29 inward to press the rollers 30 and 31 against the mandrel and the latter against the driving rollers as shown at the top of Figs. 3 and 5, whereby the mandrel is rotated on its own axis.

The parts are so arranged that the rollers 33 travel clear of the cam when passing down on the right hand side thereof as shown in Fig. 3.

It is intended that the ends of the tapes shall be applied when the mandrels reach approximately the position above shaft 16 and the winding be performed while the mandrel is passing down in front of and inward away from the operators as they stand in front of the machine which would be on the right of Fig. 1, the speed of rotation of the mandrels relative to their orbital movement being such that there is ample time for the winding of the tapes while the mandrels are traveling from gripping position to the discharge position.

In present day practice, instead of wrapping clear across the tube, the ends only of the tube are wrapped on to the mandrel, to produce the skives necessary on the end of the tube and also to prevent any air from entering between the tube and the mandrel. The main body of the tube is cured without any wrapping. The present machine is therefore designed so that while one operator is working on one end of one mandrel, the other operator is working on the opposite end of the same mandrel, both of the operators operating upon one mandrel at a time.

I have found that when the operators become experienced, it is not necessary to stop or start the machine. The operators are able to start the ends of their tape simultaneously while the machine is running. However, with operators who are less skillful or who are learning to operate the machine, it is necessary for them to stop the machines when they start the ends of their tape.

My preferred form of starting and stopping means comprises a treadle board 44 extending across the front of the base of the machine, and carried by depending levers 46 articulated to the main frame at 46a, the board being urged towards the operators or to the right, Fig. 1, by spring means indicated at 45.

One of the levers is arranged to operate a switch (indicated conventionally at 47), the arrangement being such that when an operator presses on the board, the switch is opened and the motor stopped, while when pressure on the board is relieved, the reverse operation takes place.

In actual practice, both operators would place a foot on the treadle board to hold the machine stationary while the tape ends were being attached, each removing his foot when through so that the machine would not be started until the slowest man had his tape in readiness for winding.

Of course, even when the operators are sufficiently skilled to operate while the machine is in continuous movement, occasions may arise which necessitate stopping by one or the other operators, and the arrangement shown permits either to stop the device at will without moving from his position.

It is desirable to keep the unwrapped tubes separate from each other while on the rails or runways 41 and to this end, I provide escapement levers 42 which are simply two armed levers having their anterior arms 42a heavier than their posterior arms 42b, so that said arms 42b tend to stand upward in the path of the mandrels. When the first mandrel rolls down the runway, it successively depresses all the arms 42b until it reaches the position adjacent the turrets where it will hold said arm 42b depressed and the corresponding arm 42a elevated in position to hold the next succeeding mandrel

spaced from the first, and so on with each following mandrel.

Obviously, the various parts, runway rails, turrets, and cradle, and presser rolls, would be arranged so as to contact with the uncovered ends of the mandrels or poles, so as not to damage the rubber stock and leave it free for the application of the wrapping tape.

For convenience of manufacture, the pick up hooks are formed separately from the drum being formed integral with segmental parts 19a adapted to be bolted or riveted to the turrets and having inwardly extending bracing webs 19b.

Having thus described my invention, what I claim is:

1. Apparatus of the class described comprising a pair of spaced rotatable turrets, cradle rolls rotatably carried by said turrets, means for feeding mandrels to said cradle rolls, means for pressing the mandrel ends against the cradle rolls, and means for rotating said turrets and said cradle rolls.

2. Apparatus of the class described comprising a pair of spaced rotatable turrets having mandrel end receiving recesses, rotatable cradle rolls adjacent the inner ends of said recesses, means for rotating said turrets and for rotating said cradle rolls, means for feeding mandrels to said recesses, and roller presser means for pressing the mandrels against the cradle rolls with means for operating said roller presser means.

3. Apparatus of the character described comprising a pair of spaced rotatable turrets, pairs of rotatable cradle rolls carried by said turrets, means for feeding mandrels to be positioned against said cradle rolls, means for pressing the mandrels thereagainst, and means for rotating the turrets and driving said cradle rolls.

4. Apparatus of the class described comprising a pair of spaced rotatable turrets having mandrel receiving recesses, rotatable cradle rolls adjacent the inner ends of said recesses, means for rotating said turrets and cradle rolls, means for feeding mandrels to said recesses, swinging arms adjacent said recesses, presser rollers carried by said arms, and means for swinging said arms to cause them to press the mandrels against the cradle rolls or to be moved from alignment with the recesses according to the direction of movement of the arms.

5. Apparatus of the class described comprising a pair of spaced rotatable turrets having mandrel receiving recesses, rotatable cradle rolls adjacent the inner ends of said recesses, means for rotating said turrets and cradle rolls, means for feeding mandrels to said recesses, swinging arms adjacent said recesses, presser rollers carried by said arms, and means for swinging said arms to cause them to press the mandrels against the cradle

rolls or to be moved from alinement with the recesses according to the direction of movement of the arms, comprising a lever arm operatively connected with said swing-
5 ing arms, and a stationary cam cooperating with said lever arm.

6. Apparatus for the purpose described comprising a pair of spaced rotatable turrets each having a plurality of radially ar-
10 ranged mandrel receiving recesses, rotatable cradle rolls adjacent the inner ends of the recesses, means for rotating the turrets and cradle rolls, means for successively position-
15 ing mandrels with their end portions seated in the recesses, at one point in the travel of the turrets, means at another point for re-
ceiving discharged mandrels, presser means for pressing the mandrel ends against the cradle rolls, and means for causing said press-
20 er means to be moved clear of the recesses at the receiving and discharge points, and to co-
operate with the mandrel ends between said points.

7. Apparatus according to claim 6 pro-
25 vided with starting and stopping means capable of operation by a plurality of op-
erators from different positions.

8. Apparatus according to claim 6 having starting and stopping means including a
30 movable treadle board extending the entire length of the machine and operatively connected.

9. Apparatus for the purpose described comprising a pair of rotatable turrets jour-
35 naled to rotate about a common horizontal axis, and provided with a plurality of alined radial recesses, means for rotating said turrets, mandrel supporting means adjacent the upwardly moving portions of said turrets,
40 pick up projections carried by said turrets adjacent the mouths of the recesses, mandrel driving rolls carried by the turrets having their peripheries projecting within the space defined by the walls of the recesses, means
45 for rotating said driving rolls, anti-friction presser means for cooperating with the mandrels, and means for causing said presser means to engage the mandrels on the down-
50 wardly moving side of the turrets and to be swung clear of the recesses on the lower and rising sides for discharge of mandrels from recesses and replacement thereof with fresh mandrels.

10. Apparatus of the class described com-
55 prising a shaft, a pair of turrets fast thereon, means for driving the shaft and turrets, said turrets having each a plurality of radial mandrel receiving recesses, mandrel rotating rolls positioned to engage mandrels when located
60 in said recesses, driving means connected to all of the mandrel driving rolls, lever arms articulated to said turrets and carrying presser rolls arranged to swing towards and away from said driving rolls, spring means tend-
65 ing to urge them towards the driving rolls,

and means for swinging said arm away from the presser rolls during a portion of the ro-
tation of the turret to permit entrance of the mandrels into the recesses and discharge
therefrom.

70

11. Apparatus of the class described com-
prising rotatable spaced turrets having man-
drel receiving recesses in their peripheries,
means for guiding mandrels to said recesses,
and means for supporting said mandrels 75
spaced from the walls of said recesses and ro-
tating them during the rotation of the tur-
rets.

12. Apparatus of the class described com-
prising a pair of spaced rotatable turrets,
cradle rolls rotatably carried by said turrets,
means for pressing mandrels against the
cradle rolls, and means for rotating said tur-
rets and cradle rolls.
